APPARATUS FOR TREATING SKINS, FABRIC, TOBACCO, AND THE LIKE.

1,327,668.

Specification of Letters Patent. Patented Jan. 13, 1920.

Application filed May 21, 1914. Serial No. 839,951.

To all whom it may concern:

Be it known that I, JAMES U. FLANAGAN, a citizen of the United States, residing in the city of Wilmington, county of New Castle, State of Delaware, have invented a new and useful Apparatus for Treating Skins, Fabric, Tobacco, and the like, of which the following is a specification.

My invention in its broad aspects consists of an improved method of and apparatus for treating skins, fabric, tobacco or the like, in a manner whereby the material to be dried is subjected to the action of a drying agent, comprising air at a low temperature, either in motion or stationary, which is applied directly or indirectly to the material to be dried.

In one embodiment of my invention, as herein described, I utilize the same for treating lacquered or otherwise various coated skins, whereby such skins, after the application of the lacquer or similar glazed coating thereto, can be subjected to air at a low temperature or to cold blasts of air which dry and harden the coating.

In its broad aspects, my invention is not limited in its use to skins treated as hereinabove described, but it is equally applicable to skins after the same have been oiled off, staked, seasoned or otherwise treated.

My invention further consists of an improved method of and apparatus for treating lacquered or otherwise glaze-coated skins, in which such skins after the application of the lacquer or similar glazed coating, can be subjected to cold blasts of air which dry and harden the coating.

It further consists of improved means for cooling the air-blast to which the treated skins are exposed to dry and harden the coating.

It further consists of improved means for supporting the skins to be treated.

It further consists of other novel features of construction, all as will be hereinafter fully set forth.

The annexed drawing and the following description set forth in detail one mechanical form embodying the invention, such detail construction being but one of various mechanical forms in which the principle of the invention may be used.

Figure 1 represents a longitudinal section of an apparatus embodying my invention.

Fig. 2 represents a horizontal section of such apparatus.

Similar numerals of reference indicate corresponding parts in the figures.

Referring to the drawings, the reference numeral 1 indicates an inclosure or casing, consisting of a bottom, 2, top, 3, sides, 4, an end, 5, and doors, 6, hinged to the edges of the sides to close the opposite end. All of these parts of the casing are preferably double and suitably lined or packed with non-heat-conducting material. A blower, 7, is connected to deliver a blast of air into a flaring opening, 18, in the end of the casing, and one or more suction-blowers, 8, are connected at the opposite end of the casing. A coil or manifold, 9, is supported at the end of the casing opposite to the discharge of the same, and has a pipe-connection, 10, with a cooling device, such as the brine-pump of an ice-machine or a similar source of cold. A truck, 11, having wheels, 12, can travel and rests upon rails, 13, upon the bottom of the casing, and trays, 14, having flanged sides, 15, are adapted to be stacked upon said truck so as to have longitudinal spaces between them formed by the flanges resting upon each other, and said trays have clamps, 16, which can stretch and hold skins, 17, in such space.

In practice, the skins which have been coated with lacquer or whatever glazing composition is employed, or treated with other composition, are stretched in the trays by the clamps, and the trays are piled upon the truck with the edges of the flanges of one layer of trays resting upon the edges of the flanges of the trays in the layer below, and with their open ends meeting to form longitudinal narrow passages between the trays and through the stack. When a loaded truck is placed in the casing and the latter is closed, the blast is started by the blower, the air will spread inside of the cooling chamber formed with the flaring opening in the end of the casing, and the current of air comes in contact with the cooling coil and the branches of the same and becomes cooled to a low temperature, whereupon it passes through the narrow passages between the

trays, passing over the coated sides of the skins stretched in the trays. The cold blast will chill and dry and harden the varnish, japan, lacquer or whatever coating upon the skins, and being forced into the casing at one end and drawn out by the suction blowers at the other end, such cold blast will quickly dry the skins, dispensing with the usual slow process of drying the skins out of doors, wherein a large amount of surface space is required, which is useless when no skins are dried, and which is both slow and uncertain, owing to weather-conditions.

The glazing composition requires cold air to remove its tackiness and attempts to dry skins covered with lacquer or similar glazing composition by exposing such coated skins to heat has resulted in drying the skins hard and brittle and killing all the life in the same, and as soon as the skins have been removed from the dry heat, they again become tacky. The only method hereto successful has been placing the skins stretched in frames in the outer air. Such process requires large outdoor area which, when no drying is taking place, is substantially idle, thus making the process expensive, and a considerable labor-force is required to carry and place and again remove the frames holding the skins. Atmospheric conditions, such as rain and snow, interfere by preventing the skins being placed out of doors, and the ground space for drying the skins must be located where the atmosphere is comparatively free from soot, dust or other impurities which will otherwise stick to the tacky surfaces of the skins.

By the use of my apparatus and method, ground-space in the open air is not required, and floor-space is saved, as the skins and frames are stacked above each other. The drying of the skins is not dependent on atmospheric conditions, and the skins are protected from impurities depositing upon them. The handling of the skins is simplified and the drying may be continually and expeditiously carried out with great saving of time.

The advantages of my process of effecting the drying operation by means of air at a low temperature or cold blasts of air, are the following:—

Warm air contains, ordinarily speaking, a much greater percentage of moisture than air which has been refrigerated. Owing to this fact, the warm air is manifestly incapable of absorbing from any material to be dried, the amount of moisture which can readily be taken up by refrigerated air or air at a low temperature. Another advantage of the refrigerated air is the fact that warm air has a tendency to contract and harden the substances dried, and this would not be the case with refrigerated air, but, on the contrary,

there would be a tendency to expand and soften the dried substances, and in the case of leather, it would "plump" the same more or less, which is a matter of extreme importance, leather manufacturers being extremely desirous of making their leather as plump and full as it is possible to do, owing to the fact that there is a much readier sale for it at an advanced price.

It is also possible greatly to reduce the time required in drying by the use of refrigerated air, which effects a considerable economy.

Other modes of applying the principle of my invention may be employed for the mode herein explained. Change may therefore be made as regards the mechanism thus disclosed, provided the principles of construction set forth respectively in the following claims are employed.

Having thus described my invention, what I claim as new and desire to secure by Letters Patent, is:—

1. An apparatus for treating glaze-coated skins, comprising an inclosure, means at one end of said inclosure for introducing a blast, transportation means adapted to enter said inclosure, and trays supported upon said transportation means and having spaces between them, each of said trays carrying a skin stretched thereon.

2. An apparatus for treating glaze-coated skins, comprising an inclosure, means at one end of said inclosure for introducing a blast, means for cooling said blast, transportation means adapted to enter said inclosure, and trays supported upon said transportation means and having spaces between them, each of said trays carrying a skin stretched thereon.

3. An apparatus for treating glaze-coated skins, comprising an inclosure, means at one end of such inclosure for introducing a blast, a truck adapted to enter such inclosure, and trays having flanges upon their side edges and means for supporting the skins, said trays being adapted to be stacked upon the truck with their flanges resting upon one another to form longitudinal narrow passages between them.

4. An apparatus for treating glaze-coated skins, comprising an inclosure, means at one end of such inclosure for introducing a blast, means for cooling such blast, a truck adapted to enter such inclosure, and trays having flanges upon their side edges and means for supporting the skins, said trays being adapted to be stacked upon the truck with their flanges resting upon one another to form longitudinal narrow passages between them.

5. An apparatus for treating glaze-coated skins, comprising an inclosure, means at one end of such inclosure for introducing a blast, means for cooling such blast, suction means

at the opposite end of such inclosure for removing air from the same, a truck adapted to enter such inclosure, and trays having flanges upon their side edges and means 5 for supporting the skins, said trays being adapted to be stacked upon the truck with their flanges resting upon one another to

form longitudinal narrow passages between them.
